ELECTRIC JACQUARD MECHANISM

Joseph H. Bromley, Jr., Philadelphia, Pa.

Application May 21, 1938, Serial No. 209,341

11 Claims. (Cl. 96—20)

This invention relates primarily to lace making machines of the type wherein one set of threads, commonly referred to as warp threads, is normally hung in a vertical plane, with said threads disposed in laterally spaced relation to each other, to form the foundation work of a lace fabric; and wherein a second set of threads, commonly referred to as spool threads, is correspondingly hung in an immediately adjacent vertical plane, to function as design forming threads for producing patterns in the lace fabric; and wherein mechanism is provided for shifting or shogging one or both sets of threads laterally in their respective planes; and wherein thread controlling elements, commonly referred to as jacks, are projected selectively in a horizontal plane between the threads of one or both sets prior to said lateral shoggings of said threads to effect predetermined groupings of predetermined threads of one or both sets; and wherein a third set of threads, commonly referred to as shuttle or bobbin threads, are passed, in vertical planes at right angles to the planes of said foundation and pattern sets of threads, between and around said groups, to bind the threads of each selected group together, to effect the formation of the pattern in the lace fabric.

The grouping jacks are selectively controlled ordinarily by jacquard mechanism installed at a relatively high elevation above the horizontal plane in which the jacks are mounted and operated; and the jacks are normally connected, by cords, to the needles or jack controlling elements of the jacquard mechanism.

A lace machine of the type noted may have, for example, 4,320 or 5,184 of the above noted jacks. The machine is normally constructed to produce a number of identical strips or units of lace fabric simultaneously. For that purpose the number of jacks would be divided into as many substantially equal parts or divisions as there are strips to be made at one time. The harness, i. e. the cords, between the jacquard needles and the jacks would likewise be hung in accordance with the number of strips which are to be produced at one time on the machine, and the jacquard mechanism would contain at least as many needles as there would be jacks in each division. Thus, in a machine having the smaller number of jacks above noted, and which is intended to produce six identical units at one time, there would be at least 720 needles and the cards cooperating with these needles for controlling the jacks would be laid out in 720 spaces, on each card. Each harness cord coming from each jacquard needle

in such a six division split, would be connected by complementary cords to six of the jacks of the machine, i. e. to one corresponding jack in each of the six divisions respectively.

The thread-engaging portions of the jacks are normally disposed in a horizontal plane with the ends of the jacks adjacent to but spaced from the planes in which the foundation and the pattern threads are respectively hung and are moved within said horizontal plane from said normal position to one or the other of two positions, i. e. into the plane of the pattern threads or into the planes of both the pattern threads and the foundation or warp threads, the positions of the jacks with respect to the planes of the pattern and foundation threads being governed by the cards of the jacquard mechanism through said needles and harness cords. Therefore, there is normally two harness cords for each jack, one controlling the position of the jack with respect to the pattern threads and the other for controlling the position of the jack with respect to both the foundation and pattern threads. There would then, in ordinary practice, be two jacquard mechanisms, each with a set of needles and cards employed for controlling the jacks in preparation for each grouping of the foundation and pattern threads, prior to the binding of the threads of each group together by the respective shuttle threads.

In some instances, i. e in what is known as "ordinary" lace, the jacks then function to control only the spool threads, while in other instances, in what is known as "combination" lace the jacks then function to control both the spool and the warp threads. In the first instance the two jacquard mechanism may be differently adjusted, i. e. one jacquard mechanism may be operated to hold the spool threads just long enough to make what is known in the art as a "two-gate" tie while the second jacquard mechanism may be adjusted to make what is known in the art as a "three-gait" or "four-gait" tie. In other words one operates to make light weight fabric while the second operates to make heavy weight fabric.

In other cases a single jacquard mechanism with a double set of needles and a double set of spaces on the cards may be used, wherein one half of the card and its associated needles may be employed for controlling one position of the jacks and the other half of the card and its associated needles may be employed for controlling the second position of the jacks, or alternate spaces in the card and alternate needles

respectively associated therewith may be employed. The point to be remembered is that in machines, for example, capable of producing double action "ordinary" and "combination" lace, there are two cords for controlling each jack while in machines, for example, capable of producing only "simple" patterns in single action "ordinary" lace, one cord for each jack would suffice; that in the double action ordinary and combination work one cord is connected to a needle for effecting the first position of the jack while the other cord is connected to a second needle for effecting the second position of the jack; and that it matters not whether the first position needles be assembled for cooperation with the spaces on one card and the needles for the second position assembled for association with the spaces on another card or whether one card serves both purposes, as noted.

The hanging of a harness in this type of machine requires substantially a month and costs approximately \$1,000. From this it will be readily seen that when the harness of a machine is hung for a six division split, for example, the machine is definitely set for making six strips of fabric at one time. Therefore, different machines are hung for, let us say, six strips, while other machines may be hung for either a greater number of strips or a lesser number of strips and once hung the machines are definitely adapted to make only that number of strips or a multiple thereof.

Styles in lace curtains, for example, which are made on this type of machine vary, sometimes requiring relatively narrow fabric and at other times requiring relatively wide fabric. The width of the fabric determines the number of strips that may be made simultaneously on each machine. Therefore, in order to be in a position to fill orders for a large number of variations of widths, the manufacturer is required to have a number of these expensive machines with the harness hung for each of the requirements, as it would be economically impractical to rehang the harness of each machine in accordance with the change in the widths required by the changes of style.

Obviously, each division will make a fabric strip of a definite maximum width but can be used to make a fabric of relatively lesser width. However, the number of strips made at one time remains constant, in accordance with the tie-up of the particular harness in that machine. In order to meet competition it is necessary to make as large a number of strips simultaneously as could possibly be made on the machine. It, therefore, is economically impractical to make relatively narrow strips other than multiples on machines divided to make relatively wide strips and it is economically impractical, for the reasons given above, to rehang the harness to produce the greater number of strips simultaneously.

Due to the excessive length of harness cords required to connect the jacquard needles with the various jacks of the several divisions of the machine, difficulty has been experienced as a result of contraction or elongation of the cords due to temperature and humidity variations, etc. To overcome this difficulty and in order to lower the position of the jacquard mechanism I proposed in my prior patent, No. 1,066,789, dated July 8, 1913, to substitute electric circuits for the harness cords. However, the circuits, insofar as divisional splits of the complement of jacks is concerned, correspond to the complementary

5 cords and are, therefore, equally expensive, if not more so, to make the original circuit lay-out connections or to change the lay-out to vary the number of strips to be made on the machine simultaneously.

10 My present invention is directed to an electric circuit system corresponding to that disclosed in said prior patent. The object of the present invention is to provide interchangeable mechanism in the circuit by which changes from one 15 divisional set-up to another divisional set-up may be readily accomplished in an extremely short period of time and at relatively low cost, by which such changes are made economically practical.

15 The above noted object of the invention is accomplished by connecting each needle of the jacquard mechanism to a terminal of one series mounted on one terminal panel and the jack controlling solenoids respectively to terminals 20 on a second terminal board disposed in a plane parallel to the first mentioned terminal board; and providing a readily removable and replaceable division unit between the two terminal boards, in which on one face of the unit is 25 provided with a series of contacts corresponding to the terminals on the first said terminal board and on its opposite face with a series of contacts corresponding to those on the second of said terminal boards, and between the opposite faces 30 of said replaceable unit connecting each of the contacts which correspond to the primary terminal board with each of a plurality of the contacts corresponding to the terminals on the secondary terminal board.

35 With the above arrangement it is possible to make up any desired number of the above noted interchangeable units, each for a different divisional hook-up, i. e. one unit may be arranged with each primary contact connected to six 40 secondary contacts. Another unit may have each primary contact connected to five secondary contacts. Another unit may have each primary contact connected to nine secondary contacts and so on in a practically unlimited number of combinations, each combination representing the number of divisions into which the complement of jacks in the machine will be split for making a corresponding number of fabric strips simultaneously. Therefore, when it is desired to change the division of the machine from, for example, a six strip hook-up to a nine strip hook-up it is only necessary to remove the interchangeable divisional unit for the six split division and insert in place thereof the divisional 55 unit for the nine split hook-up. This change may be made in a relatively few minutes and will require substantially no idle period of the machine as a whole; and the expense involved is substantially nil, after the divisional unit has 60 once been wired for a definite combination. After initial wiring, the unit may be kept on hand for substitution in the machine whenever that particular divisional split of the machine is desired.

65 In the accompanying drawings:

Fig. 9 is a sectional elevation of a detail of construction;

Fig. 10 is a fragmentary view showing a portion of the mechanism in Fig. 9, in front elevation; and

Fig. 11 is a modification of the hook-up shown in Fig. 7.

The construction and operation of the machine to which the present invention is particularly applicable is clearly shown and described in the above noted prior patent, therefore, it is believed that detailed description thereof in the present case is unnecessary.

In Fig. 7 of the drawings of the present case, several of the elements of the machine are disclosed, to illustrate the application of the present invention thereto. In said figure the set of warp threads is illustrated at *a*; and the set of pattern threads is illustrated at *b*. The spring jacks are illustrated at *1*, the jack rods at *2*, each jack rod being provided with a pair of abutments *3* and *4* respectively for cooperation with the upper portion *5a* of the two part jack controlling stop *5*, the two parts *5a* and *5b* of the stop *5* being associated with solenoid coils *6a* and *6b* respectively of a single solenoid unit.

One side of each of the coils *6a* and *6b* is connected by a wire *7* to one side of a source of electric energy *8*, the second side of which is connected by a wire *9* to a plate *10* of the jacquard mechanism in which is slidably mounted a needle *11* for controlling one position of the jack stop *5* and its associated jack *1*; and a needle *12* for controlling a second position of the jack stop *5* and jack *1*, said needles being respectively adapted to effect closing of circuits with contacts *13* and *14* respectively.

For the purpose of illustration, the needles *11* and *12* are shown as being in the same jacquard mechanism and adapted to be actuated by a single card, however, as noted above, the needles *11* and *12* may be in different jacquard mechanisms respectively.

The contact *13* is connected by a wire *15* to a primary terminal *17* which is supported in a primary terminal board *A* (see Figs. 1 and 2). The needle *12* is adapted to effect closing of a circuit with a contact *14* which is connected by a wire *16* to a primary terminal *18* also mounted in the primary terminal board *A*.

The second side of the coil *6a*, which provides a full-lift for the upper portion *5a* of the two part jack stop *5* into the path of the abutment *3* of the jack rod *2*, is connected by a wire *19* to a secondary terminal *21* mounted in a secondary terminal board *B* (see Figs. 1 and 2). The second side of the coil *6b*, which effects a half-lift of the jack stop *5* into the path of the abutment *4* of the jack rod *2*, is connected by a wire *20* to a secondary terminal *22* which is carried by the secondary terminal board *B*.

75 Connection between the full-lift and half-lift

primary terminals *17* and *18* of the primary terminal board *A* are made with the full-lift and half-lift secondary terminals *21* and *22* respectively, which are carried by the secondary terminal board *B*, through a readily removable division unit *C*.

As shown in Fig. 7, the primary terminal *17*, of the primary terminal board *A*, makes contact with a primary contact *23* on one side of the division unit *C* and the secondary terminal *21*, of the secondary terminal board *B*, makes contact with a secondary contact *25* on the second side of the division unit *C*. The contacts *23* and *25* of the division unit *C* are connected within the unit *C* by a wire *27*.

In a like manner the primary terminal *18*, carried by the primary terminal *A*, makes contact with a primary contact *24* on the first said side of the division unit *C*. The secondary terminal *22* carried by the secondary terminal board *B*, makes contact with a secondary contact *26* carried by the second side of the division unit *C*. The primary and secondary contacts *24* and *26* are connected within the unit *C* by a wire *28*.

As noted above the division unit *C* may be arranged for any desired divisional split of the jacks of the machine. Therefore, each of the primary contacts *23* and *24* in the one side of the division unit *C* has connected to it a plurality of wires *27* and *28* respectively, as illustrated at *27a* 30 and *28a* in Fig. 7, the number of connections depending upon the divisional split for which that particular unit *C* is wired. Each one of the wires *27* of the group *27a* is connected to a different secondary contact *25* in the second side of the unit *C*, 35 for supplying current to the full-lift coil *6a* with which the particular secondary contact *25* is connected.

In a like manner each of the wires *28* of the group *28a* is connected to a separate secondary contact *26* for supplying current to the half-lift coil *6b* with which the secondary terminal *22* is connected.

Thus, assuming that the unit *C* is hooked up for a six split division, each time the needle *11* is 45 operated to close the circuit through the switch contact *13*, wire *15*, primary terminal *17* and primary contact *23* that circuit will be split six ways from the primary contact *23* to six individual secondary contacts *25* and thereby complete circuits through six secondary terminals *21*, wires *19*, coils *6a* and wires *7* to the source of energy *8*, it being understood that the circuit from the opposite side of the source of energy is completely through the wire *9* and plate *10* to the needle *11* 55 and switch contact *13*.

In a like manner each time the half-lift needle *12* is operated to make contact with the switch contact *14* a circuit is completed from the one side of the source of energy *8* through the wire *9* and plate *10* to the needle *12* and from the needle *12* through the switch contact *14*, the wire *16* and the primary terminal *18* to the primary contact *24*. From the primary contact *24* the circuit is split six ways through the wires *28a* to six individual 65 and separate secondary contacts *26*, each of which, through its cooperating secondary terminal *22* and wire *20* closes the circuit to a half-lift coil *6b*, the second side of which is connected by a wire *1* to the source of energy *8*.

70 It will be understood that in a machine having, for example, 4,320 jacks, the division for making six fabric pieces at one time would provide 720 jacks in each division and the connections through the divisional unit *C*, between the contacts *23* and *25*

25, and 24 and 26, would be so arranged that when the needles 11 and 12 operate jack number 1 in any one unit they would operate the corresponding jack number 1, at the same time, in each and 5 all of the six divisions. The same relation would obtain through the whole, of the 720 jacks for each fabric strip.

A corresponding relationship would exist in each of the other divisions, for example, in the 10 five split division, the corresponding jacks at each division would be simultaneously operated. In a nine split divisional hook-up the corresponding jacks in each of the nine divisions would be operated in a like manner.

15 The structure for providing the desired division may vary without departing from the spirit of the invention. In the present instance, the primary terminal board A, as shown in Fig. 5, has the full-lift and half-lift terminals 17 and 18 20 for each jack arranged in immediately adjacent relation to each other; and suitably insulated from each other, as illustrated at 30. The primary contact board A1 of the division unit C likewise has the contacts 23 and 24 for each jack 25 arranged in immediately adjacent relation to each other; and insulated from each other, as indicated at 31 in Fig. 5.

Each of the contacts 23 has secured to it a 30 number of wires 27a corresponding to the division which is to be made by the particular unit C. The contacts 24 each have a corresponding number of wires 28a attached to its inner end. The inner ends of the contacts 23 and 24 project into the hollow interior 32 of the unit C, between the 35 primary and secondary contact boards A1 and B1 thereof.

The individual wires 27 of the group 27a extend through the space 32 to the individual secondary contacts 25, carried in the secondary contact 40 board B1 of the unit C and the individual wires 28 of the group 28a, connected to each of the contacts 24, correspondingly extend through the space 32 of the unit C to the individual secondary contacts 26 in the terminal board B1 of the unit C.

45 As shown in Fig. 6, the secondary contacts 25 and 26 are arranged in immediate adjacent relation to each other and insulated from each other as indicated at 33. The contacts 21 and 22 in the secondary terminal board B are likewise arranged in immediate adjacent relation to each other and insulated from each other as illustrated at 34 in Fig. 6.

It will be understood, of course, that in the 55 making of some of the divisions all of the primary terminals 17 and 18 may not be employed, for example, in a nine division split the 4,320 jacks would be divided into nine equal parts of 480 jacks each. Consequently, instead of 720 primary terminals 17 and 18 and their associated 60 needles 11 and 12 being put into use only 480 would be operative at such a time, the remaining primary terminals and needles being idle. The corresponding spaces on the jacquard cards would likewise remain blank.

65 The jacks 1 as noted in the above prior patent are composed of spring steel and are all rigidly connected at their lower ends to a rock bar 60. This bar is oscillated by a cam 61 and tends to move the entire full complement of jacks as a 70 body from the normal position shown in Fig. 7 to a position wherein each and all of the jacks would be projected through the planes of both series of threads a and b. However, and depending upon the pattern to be made, one of the 75 cards 62 of the jacquard mechanism has previous-

ly been moved into contact with the ends of the needles 11 and 12 and has selectively operated said needles to raise some of the stops into the path of the jack rod abutments 3 and some into the path of the jack rod abutments 4, whereby 5 some of the jacks will remain substantially in their normal position while others will be permitted to move half-way from said normal position into the plane of the threads b while others will be projected through the threads b into the 10 plane of the threads a.

When producing double action regular work, i. e. when the tips of the jacks penetrate only the spool threads and never the warp threads, the cam follower 61a is adjusted and the arm 60a 15 so that the cam 61 will project the tips of the jacks only into the spool threads and the contacts 23 and 24 are jointly connected to single contacts 25 so that both jacquard mechanisms would operate only the solenoids 6a, leaving the solenoids 20 6b inoperative. (See Fig. 11).

The wires connecting the switches 13 and 14 to the terminals on the terminal board A and those connecting the coils 6 to the terminals on the terminal board B as a matter of convenience 25 are grouped together in the form of cables and may be secured in frames shown in Figs. 1, 2, 9 and 10.

As shown in Figs. 1, 2 and 4, the terminal boards A1 B1 of the division unit C are carried by a rigid 30 frame 34, in laterally spaced relation to each other, in parallel relatively spaced planes, to provide the wire space 32 therebetween. The frame 34 is provided with feet 35 adapted to rest on horizontal supporting frame member 36, on which 35 the frame 34 is adapted to slide. The secondary terminal plate B is likewise carried by a rigid frame 37 provided with lugs or feet 38 which rest on the supporting member 36 and are secured thereto against movement by bolts or screws 39. 40 The primary terminal plate A is rigidly mounted in a rigid frame 40 which is provided with supporting brackets 41 having feet 42 adapted to slide on the supporting member 36.

Connecting the supports 36, 36, and secured at 45 its opposite ends respectively thereto, is a transverse element 43 (Fig. 3), in which is secured a nut 44 (Fig. 8). Threaded through the nut 44 is a jack screw 45. At the outer end of the jack screw is a hand wheel 46, by which the screw 45 50 may be rotated with respect to the nut 44. As a result of the pitch of the screw 45 axial movement of said screw is provided. The inner end 47 of the screw 45 is rotatably mounted in a bearing 48 carried by a spider 49, the legs of which are 55 connected by screws or bolts 50 to the marginal edges of the frame 40 in which the primary terminal plate A is secured. The jack screw 45 is provided for moving the primary terminal board A and unit C relative to the secondary terminal board B, for properly making and breaking engagement between the various spring contacts, 17, 18, 23, 24 and 21, 22, 25, 26.

Due to the relatively large number of contacts on the terminal boards B and B1 it is necessary, 65 when removing a division unit C, to provide the jack screw or other equivalent power means for separating the contacts of the terminal board B1 from the contacts of the terminal board B. For this purpose the unit C is provided at each side 70 with a lug or other projection 51 arranged to be engaged by a hook 52 of a latch 53, one of which is pivotally connected at 54 to each of the opposite sides of the frame 40.

With the terminal boards A and B spaced 75

apart as shown in Fig. 2, a unit C may be readily placed between or removed from between the two. To effect a hook-up, a unit C of desired division is placed between the terminal boards A 5 and B, as illustrated in Fig. 2. The jack screw 45 is then rotated by means of the wheel 46 to advance the frame 40 and the terminal board A carried thereby toward the frame 34 of the unit C, until the contacts on the terminal board A 10 engage the contacts on the terminal board A' of the unit C. Further rotation of the jack screw 45 slides the frame 40 along the supports 36 and pushes the unit C along said supports in advance thereof, until the contacts carried by 15 the terminal board B' of the unit C engage the contacts carried by the stationary terminal board B. Further rotation of the jack screw 45 consolidates the engagement between all of the contacts and brings the faces 55 and 56 of the frame 34 into firm contact with the faces 57 and 20 58 to the frames 37 and 40 respectively, as illustrated in Fig. 1. The unit is then ready for operation.

At such time the hook 52 of the latch 53 is 25 behind the lug 51 of the frame 34. When it is desired to separate the contacts, to remove the unit C, the jack screw 45 is turned in an opposite direction from that previously described.

The jack screw 45 first pulls the frame 40 and 30 separates the terminals of the board A from the contacts of the board A' of the unit C. The hooks 52 then engage and pull the unit C away from the frame 37 and withdraw the contacts of the terminal board B' of the unit C from the contacts of the stationary terminal board B, 35 which, as noted, is held in a definitely fixed position. Continued rotation of the jack screw moves the frame 40 and unit C until cam faces 53a on the latches 53 engage trip pins 55 on the supports 36. This releases the latches 53 from the 40 unit C permitting it to stand while the frame 40 continues to move to the position shown in Fig. 2. The unit C may then be removed and another set in its place on the supports 36, 36.

The wires 15 and 16 between the switches 13, 45 14 and the terminals 17 and 18 are combined in cables 62 and the wires 19 and 20 between the coils 6a, 6b, and the terminals 21 and 22 are combined in cables 63. These cables are clamped 50 in definite position by clamps 64 and 65 carried by the frame 66 which is rigidly secured in place on the supports 36, 36.

While the device has been described, for the 55 purpose of illustration, in connection with a lace making machine it will be obvious that its use is in no way restricted to such machines; and the device may be employed with any apparatus employing jacquard mechanism or other equipment where a large number of elements are to be divided into groups, wherein the groups are 60 subject to change as to numbers in each group; and wherein the groups are to be controlled from a single source.

I claim:

65 1. In a jacquard controlled machine comprising a relatively large number of elements to be controlled and a relatively smaller number of jacquard actuated controlling elements completely disconnected from all said large number of elements, an interchangeable division unit interposed between said controlled and said control elements comprising means for operatively connecting each of said control elements to each of a predetermined number of said controlled 70 elements.

2. In a lace making machine comprising a relatively large number of thread controlling jacks and a relatively smaller number of jack controlling elements completely disconnected from all of said jacks, an interchangeable division unit interposed between said jacks and said control elements comprising means for operatively connecting each of said control elements to each of a predetermined number of said jacks. 5

3. In a lace making machine comprising a relatively large number of thread controlling jacks, a relatively smaller number of jack controlling elements for governing movement of said jacks and completely disconnected from all of said jacks, and a division unit interposed between 10 15 said jacks and said controlling elements including means for operatively connecting each of said controlling elements to each of a predetermined number of said jacks.

4. In a lace making machine comprising a relatively large numbered series of independently operable thread controlling jacks, a relatively smaller numbered series of jack controlling elements for governing movement of said jacks and completely disconnected from all of said jacks, 20 25 a second corresponding small numbered series of jack controlling elements for governing movement of said jacks also completely disconnected from all of said jacks, a division unit interposed between said jacks and said controlling elements 30 including means for operatively connecting each of the controlling elements of said series to each of a predetermined number of said jacks.

5. In a lace making machine comprising a relatively large number of thread controlling jacks 35 each movable to either of two positions with respect to said threads, a relatively smaller number of jack controlling elements for governing the movement of said jacks to one of said positions and completely disconnected from all of 40 said jacks, a corresponding small number of jack controlling elements for governing the movement of said jacks to the other of said two positions also completely disconnected from all of said jacks, a division unit interposed between said 45 jacks and said controlling elements including means for operatively connecting each of said first and second position controlling elements to each of a predetermined number of said jacks.

6. In a lace making machine comprising a relatively large number of thread controlling jacks, means common to all of said jacks for advancing said jacks as a body to a predetermined extent in one direction from a normal position thereof, an individual stop for each jack, a relatively smaller number of stop controlling elements, and an interchangeable division unit interposed between 50 55 said stops and said elements and comprising means for operatively connecting each of said elements to each of a predetermined number of said stops.

7. In a lace making machine comprising a relatively large number of thread controlling jacks, means common to all of said jacks for advancing said jacks as a body to a predetermined extent in one direction from a normal position thereof, an individual stop for each jack movable to two positions from a normal position for governing the advance positions respectively of said jack, a relatively smaller number of stop controlling elements for governing one of said positions of said stops, a similar relatively small number of stop controlling elements for governing the second of said positions of said stops, an interchangeable 70 75 division unit interposed between said stops and 75

said stop controlling elements including means for connecting each of said first position stop controlling elements with each of a predetermined number of said stops, and means for connecting 5 each of said second position stop controlling elements with the same stop respectively to which said first position stop controlling elements are connected.

8. In a lace making machine comprising a relatively large number of thread controlling jacks, a relatively smaller number of jack controlling elements, an electric switch operable by each of said jack controlling elements, an electrically operable regulating device for each jack, an individual primary terminal for and electrically connected to each of said switches, a secondary terminal for and electrically connected to each of said regulating devices, a division unit interposed between said primary and secondary terminals and comprising a series of contacts detachably engaging said primary terminals respectively, a series of contacts detachably engaging said secondary terminals respectively, and means electrically connecting each of said primary contacts 20 with each of a predetermined number of said secondary contacts.

9. In a lace making machine comprising a relatively large number of thread controlling jacks, means for advancing said jacks as a body to a predetermined extent in one direction from a normal position thereof, an electrically operable stop for each jack movable to either of two positions for governing the extent of advance of each jack, a relatively smaller number of jack stop controlling elements for governing one of said stop positions, a similar small number of stop controlling elements for governing the second of said stop positions, first and second position electric switches operable by said first and second position stop controlling elements respectively, first and second position primary terminals electrically connected respectively to said switches, first and second position secondary terminals electrically connected in pairs to said stops, an interchangeable division unit interposed between said primary and secondary terminals and comprising a series of contacts respectively detachably engaging said first and second position primary ter-

minals, a series of contacts respectively detachably engaging said first and second position secondary terminals, and means electrically connecting each first and second position primary contact with each of a predetermined number of said pairs of first and second position secondary contacts. 5

10. An electric division unit comprising a primary terminal board supporting a series of primary terminals, a secondary terminal board supporting a series of secondary terminals, a frame intermediate said primary and secondary terminal boards and including a board adjacent said primary terminal board and supporting a series of contacts detachably engaging said primary terminals, a second board adjacent said secondary terminal board and supporting a series of contacts detachably engaging said secondary terminals, and means intermediate said contact boards for electrically connecting each of a predetermined number of said primary contacts with each of a group of said secondary contacts. 10 15

11. An electrical apparatus comprising a primary terminal board supporting a series of primary terminals, a secondary terminal board supporting a series of secondary terminals, an interchangeable division unit comprising a frame intermediate said primary and secondary terminal boards and including a board adjacent said primary terminal board for supporting a series of contacts detachably engaging said primary terminals, a second board adjacent said secondary terminal board for supporting a series of contacts detachably engaging said secondary terminals, means intermediate said contact boards for electrically connecting each of a predetermined number of said primary contacts with each of a group of said secondary contacts, means for supporting said frame and said terminal boards in predetermined relation to each other to maintain 20 25 30 35 40 45 said engagement between said terminals and said contacts, and means for forcibly effecting engagement and separation of said terminal boards from said frame and the contact boards and contacts carried thereby and the terminals respectively carried thereby for effecting interchangeability of said unit. 45
